8 Claims. (Cl. 20—40.5)

The present invention relates to a clear-view window with a rotating pane, and is particularly suitable for use with clear-view windows in which the rotating pane is mounted in the centre of a fixed window pane. With such windows there is the danger of precipitations occurring in the interspace between the rotating and fixed panes, and this may be avoided by a fan provided on the peripheral edge of the rotating pane.

According to the invention, a clear-view window comprises a revolving pane, driving means therefor, and mounting means for the driving means and the revolving pane, having a fan arranged to force air towards the periphery of the pane through a gap between the pane and the mounting means.

This fan may be arranged preferably within the zone of the gap between a rim of the revolving pane and the frame of the clear-view window. This ventilation produces a continuous flow of air from the inside towards the outside and eliminates effectively the entry of water and air.

The fan is conveniently designed as a radial fan. For this purpose, an annular projection connected to the window rim may be designed as a bucket or paddle ring, for example, by being provided with a simple row of holes or an oblique recess.

Embodiments of the invention will be described, by way of example, with reference to the accompanying drawing, in which:

FIGURE 1 is an axial cross-sectional of one embodiment of a clear-view window with external drive;

FIGURE 2 is a fragmentary cross-section through the window rim and window frame of another clear-view window with a center drive, and

FIGURE 3 is a fragmentary view of one form of the window rim of FIGURE 2.

The clear-view window shown in FIGURE 1 consists substantially of a revolving rotating pane 1, connected in the center by a threaded ring 2 to a threaded bush 3. The threaded bush 3 is arranged to receive the end 4 of a shaft 5. The pane 1, bush 3, and shaft 5 are firmly interconnected by a cover 6 and a shaft flange 7, which are secured together by a bolt 8.

The shaft 5 is located in two ball bearings 9 and 10, and secured against axial displacement by circular clips 11 and 12. The bearings 9 and 10 are mounted in a common bearing spindle 13 which is firmly fixed by a threaded cap 14 in a window pane 15, for example, in the porthole in the wheelhouse of a vessel.

The pane 1 is driven by an electric motor, surrounding the pane in the form of a ring. The rotor 16 of the motor, having a winding 16a, forms the rim of the pane, and a stator 17, having a winding 17a, forms the window frame or a part thereof. In the embodiment of the drawing, the electric motor is a squirrel cage rotor A.C. motor. The air gap 18 forms also the gap between the revolving window section and the window frame.

This air gap forms the inner part of a labyrinth-like channel extending from a space between panes 1 and 15 to the outside of the assembly, the configuration of which is arranged to prevent the ingress of water. In order to form this labyrinth channel, the rotor 16 carries an

2

annular projection 19 of L-shaped cross-section, the outer part 20 of which embraces the stator 17. Similarly, the stator carries an annular projection 21 of double-L-shaped cross-section, forming, together with the outer part 20 of the annulus 19, an annular chamber 22. Within this annular chamber 22, the outer part 20 of the annulus 19 carries a row of holes 23, extending over the entire circumference. In this way, the outer part 20 is given the properties of a fan through which the air is drawn from the space 24 between the revolving pane 1 and the fixed pane 15, and forced towards the outside. Thus, both the entry of air and water from the outside is avoided, and effective protection is provided against the misting over of the window. Part of the motor winding may be arranged to constitute a heater winding.

The part 20 of the annulus 19 has a triangular cross-section so that the diameter of its inner surface—viewed from the inside towards the periphery, that is to say in the direction of the flow of air—increases, and also the outside has a diameter increasing from the inside towards the outside. In this way, any water entering into the labyrinth channel and chamber 22 is forced towards the outside by the centrifugal force, as soon as it reaches the revolving part 19, 20.

The fan need only have a comparatively small delivery output, and this has the advantage that the fan noise may be reduced to a minimum. The low noise generation of the embodiment of the fan shown in the drawing is due especially also to the fact that the ring of holes is not faced by a stationary ring, located at a small distance therefrom, and that the ring faces towards the inside of the larger air chamber 22. Noise may be further reduced by arranging the hole 23 obliquely, as shown with respect to groove 33 in FIGURE 3, although this is optional.

In order to cause a circulation of air in the space 24 with gas-tight arrangements, that is to say, in the case of a gas-tight joint between the pane 15 and the wall 25 of the room and bearing cap 14, an air duct 26 is provided in the pane 15, communicating at 27, immediately adjacent to the bearing spindle 13, with the space between panes 1 and 15 and at 28 with an air duct leading outside.

The stator or frame 17 for the revolving pane 1 is connected firmly with the porthole window 15 by a ring 29 and bolts 30.

In the embodiment of a clear-view window shown in FIGURE 2 with center drive, the outer annulus 20 is formed with holes 23a, open towards the edge of the annulus. In this manner, the air present in these holes is forced not only radially towards the outside, but also axially into an outlet 31 of the labyrinth channel, and thereby assists the circulation of air from the inside towards the outside. Preferably, the holes 23a have the form of grooves, sloping contrary to the sense of rotation. A further annulus 32 is fitted on the inside of the rim 16. This inner annulus is equipped, in the same way as the outer annulus 20, 23a, with grooves 33, open towards the gap and positioned obliquely against the direction of rotation, so that the flow of air towards the outside in the adjacent zone of the gap 18 is encouraged and water, adhering to the walls of the gap opposite the annulus, is carried along. Also here the section of the gap wall and the annulus 32 have diameters increasing in the direction of flow.

The present invention may be modified and changed in many respects without departing from its principle. In particular, the arrangement of a fan within the range of the gap between rim and frame of the revolving pane of the clear-view window may be applied to clear-view windows of any design, for example, with drives by means of a flexible shaft, by belts, or from the central

motor. Furthermore, the ventilation may be effected without the aid of outer annulus 20 such as is shown in FIGURE 2.

We claim:

1. A clear view window construction comprising a rotatable transparent window spaced substantially parallel to a fixed transparent window, said rotatable window and said transparent fixed window defining a space therebetween, supporting means for said rotatable transparent window comprising a centrally located shaft means, an annular rim surrounding said rotatable transparent window and joined thereto, said annular rim carrying fan means for continuously forcing air towards and out from the periphery of said rotatable window from said space upon rotation of said window, said annular rim defining a portion of a labyrinth channel passing from said space to said periphery, a duct means for allowing entrance of outside air to said space at a point remote from said fan means, and drive means associated with said rotatable window for causing rotation thereof.

2. A clear view window construction comprising a rotatable transparent window spaced from a fixed transparent window; said rotatable window and said transparent fixed window defining a space therebetween, supporting means for said rotatable window comprising a centrally located shaft means, an annular rim surrounding said rotatable transparent window and joined thereto in gastight relationship, said annular rim carrying fan means for forcing air towards the periphery of said rotatable window from said space upon rotation of said rotatable window, fixed means mounted on said fixed window in gastight relationship therewith, spaced from said rim and cooperating with said rim to define a labyrinth channel extending from said space to said periphery, said labyrinth channel comprising an annular air gap adjacent said rim and an annular space adjacent said fan means with said annular space positioned outwardly of said air gap from said central shaft and means for allowing entrance of air to said space at a point remote for said fan means.

3. A clear view window construction in accordance with claim 2 wherein said fan means comprises a projection from said rim, said projection defining openings therein which act as a means for impelling fluid from said space between said windows to a surrounding atmosphere.

4. A clear view window construction in accordance with claim 2 wherein said shaft means is mounted on said fixed window and said space has a larger cross sectional area than said gap.

5. A clear view window construction comprising a rotatable transparent window spaced substantially parallel to a fixed transparent window, said rotatable window and said transparent fixed window defining a space therebetween, mounting means for said rotatable window comprising a centrally located shaft means, an annular rim surrounding said rotatable transparent window and joined

thereto in gastight relationship, said annular rim carrying fan means for continuously forcing air towards the periphery of said rotatable window from said space upon rotation of said rotatable window, fixed means spaced from said rim and cooperating with said rim to define a labyrinth channel extending from said space to said periphery, said labyrinth channel comprising an air gap adjacent said rim and an annular space adjacent said fan means with said annular space positioned outwardly of said air gap from said central shaft, said annular rim and said fixed means comprising portions of an annular electric driving motor for revolving said rotatable window with said air gap spacing said fixed means from said annular rim, and duct means leading from said space to a surrounding atmosphere with said duct means and said labyrinth channel together comprising the only fluid communication passageways between said space and the surrounding atmosphere.

6. A clear view window in accordance with claim 5 wherein said fan means comprises an annulus defining a plurality of openings passing through the annulus from said annular space to a surrounding atmosphere.

7. A clear view window in accordance with claim 6 wherein said openings comprise channels lying in a plane and each of said channels are inclined from radii passing through said shaft means.

8. A clear view window construction comprising a rotatable transparent window having an outer rim and being spaced substantially parallel to a fixed transparent window mounted in gas-tight relationship on an outer side of a wall,

35 said rotatable window and said transparent fixed window defining a space therebetween and having gas-tight means sealing all portions of a space defined between the fixed and rotatable windows with the exception of a portion of said space at said outer rim and ducting means communicating with said space and with the surrounding atmosphere on the outer side of said wall for allowing air flow through said space, and said outer rim comprising fan means for drawing air from said space to said outside atmosphere.
